US00D913096S

(12) **United States Design Patent** (10) **Patent No.:** **US D913,096 S**
(45) **Date of Patent:** **** Mar. 16, 2021**

(54) **PEDESTAL FOR CONTAINER**

(71) Applicant: **AICELLO CORPORATION**,
Toyohashi (JP)

(72) Inventors: **Masayoshi Kobayashi**, Toyohashi (JP);
Yoshimichi Kutsuna, Toyohashi (JP)

(73) Assignee: **AICELLO CORPORATION**,
Toyohashi (JP)

(**) Term: **15 Years**

(21) Appl. No.: **29/679,666**

(22) Filed: **Feb. 8, 2019**

(30) **Foreign Application Priority Data**

Aug. 10, 2018 (JP) 2018-017720

(51) **LOC (13) Cl.** **09-07**

(52) **U.S. Cl.**

CLAIM

The ornamental design for pedestal for container, as shown and described.

DESCRIPTION

FIG. 1 is a front view of a pedestal for container, showing our new design;

FIG. 2 is a right-side view thereof;

FIG. 3 is a top view thereof;

FIG. 4 is a bottom view thereof;

FIG. 5 is a cross-sectional view thereof, taken along line 5-5 in FIG. 3; and,

FIG. 6 is a perspective view thereof.

1 Claim, 6 Drawing Sheets
